UNITED STATES PATENT OFFICE.

FRANCOIS JOSEPH DE SPOTURNO COTY, OF PARIS, FRANCE.

DESIGN FOR A TALCUM-POWDER CAN.

Application filed November 23, 1922. Serial No. 4,378. Term of patent 14 years.

To all whom it may concern:

Be it known that I, FRANCOIS JOSEPH DE SPOTURNO COTY, a citizen of the Republic of France, residing in the city of Paris, France, have invented a new, original, and ornamental Design for a Talcum-Powder Can, of which the following is a specification, reference being had to the accompanying drawing, forming a part thereof.

In the drawing,

Figure 1 shows a perspective view of the front of the can,

Figure 2 is a side view, and

Figure 3 is a top plan view, it being noticed that the facet A is flat and not curved in the drawing.

I claim:—

The ornamental design for a talcum powder can substantially as shown.

FRANCOIS JOSEPH de SPOTURNO COTY.
